UNITED STATES PATENT OFFICE.

CARLOS ALFRED ELKINS, OF DUNNING, NEBRASKA.

DUPLICATOR.

Application filed December 27, 1924. Serial No. 758,456.

To all whom it may concern:

Be it known that I, CARLOS A. ELKINS, a citizen of the United States, residing at Dunning, in the county of Blaine and State 5 of Nebraska, have invented new and useful Improvements in Duplicators, of which the following is a specification.

This invention relates to a duplicating device, the general object of the invention being 10 to provide a hinged case for enclosing the duplicating surfaces so that they will be protected from dirt and dust and also to make the surfaces interchangeable so that a new surface can be put in place when the old one has become worn or unfit for use.

This invention also consists in certain other features of construction and in the combination and arrangement of the several parts, to be hereinafter fully described, 20 illustrated in the accompanying drawings and specifically pointed out in the appended claims.

In describing my invention in detail, reference will be had to the accompanying 25 drawings wherein like characters denote like or corresponding parts throughout the several views, and in which:—

Figure 1 is a view showing how the invention is used.

30 Figure 2 is a perspective view showing the case in closed condition.

Figure 3 is an enlarged plan view with one of the surfaces partly removed.

Figure 4 is a section on line 4—4 of Figure 3.

Figure 5 is a section on line 5—5 of Figure 3.

Figure 6 is a view of one of the locking pins.

40 As shown in these views, I provide a case A for receiving the duplicating surfaces which are shown at 1. This case is formed of two sections 2 and 3 which are hinged together, as at 4. Each surface 1 is carried by a plate 5 which slides in guideways 6 formed in each section of the case, the parts

being so arranged that the surface 1 is below the top edge of the section so that when the sections are closed the surfaces will be spaced apart. Each plate 5 is connected to 50 an end piece 7 which is detachable from each section of the case and provides a handle for sliding the plate 5 and the surface thereon into and out of the section. A pin 8 is carried by each end piece for engaging 55 a hole in the section so as to hold the end piece with its plate in closed position in the section.

By opening the case as shown in Figure 1 the letters or other matter can be duplicated 60 in the usual manner and when not in use by closing the case the surfaces are kept free of dust and dirt. If anything should happen to a duplicating surface so as to render it unfit for use it can be removed and a new 65 one substituted very easily.

It is thought from the foregoing description that the advantages and novel features of my invention will be readily apparent.

I desire it to be understood that I may 70 make changes in the construction and in the combination and arrangement of the several parts, provided that such changes fall within the scope of the appended claims.

What I claim is:—

1. A device of the class described comprising a sectional case, the sections of which are hinged together, a plate slidably mounted in each section so that it can be removed therefrom and a duplicating surface 80 carried by each plate.

2. A device of the class described comprising a sectional case, the sections of which are hinged together, guideways formed in each section, a plate engaging the guideways 85 of each section, an end piece connected with each plate, a duplicating surface carried by each plate and a pin for holding the plate and end piece in closed position.

In testimony whereof I affix my signature.

CARLOS ALFRED ELKINS.
